Primary Examiner — Paula Greene(74) *Attorney, Agent, or Firm* — Kilpatrick Townsend & Stockton LLP(57) **CLAIM**

The ornamental design for an ear piece, as shown and described.

DESCRIPTION

FIG. 1 is a front perspective view of an ear piece showing our new design;

FIG. 2 is a rear perspective view thereof;

FIG. 3 is a top plan elevational view thereof;

FIG. 4 is a front elevational view thereof;

FIG. 5 is a bottom plan elevational view thereof;

FIG. 6 is a right side elevational view thereof; and,

FIG. 7 is a left side elevational view thereof.

Broken lines showing on the drawing disclosure are for illustrative purposes only and form no part of the claimed design.

1 Claim, 6 Drawing Sheets(56)
